UNITED STATES PATENT OFFICE

FRANK OSCAR PRIOR, OF TULSA, OKLAHOMA, ASSIGNOR TO FOUR WHEEL DRIVE AUTO COMPANY, OF CLINTONVILLE, WISCONSIN, A CORPORATION OF WISCONSIN

FISHTAIL POINT FOR AUGERS

Original application filed September 12, 1927, Serial No. 219,051. Divided and this application filed January 30, 1930. Serial No. 424,534.

This invention relates to improvements in fish-tail points for augers.

It is the particular purpose of the invention to provide a point for earth boring auger adaptable to be used in shale, loose rock, or gravel. In an earth boring auger the ordinary point is not suitable in that it fails to include adequate means for cutting and breaking material at the center of the hole.

10 The present invention seeks to overcome the deficiencies of previously known points in this regard.

Fish-tail bits are well known in the earth boring art. The present invention relates 15 to a specific form of cutting surface of a fish-tail bit, and more particularly it relates to a novel relation of cutting edges and bevelled surfaces on the working end of the bit.

It is an object of the invention to provide 20 a bit having a working surface and cutting edges of such form that grinding thereof, including the original manufacturing operation and subsequent sharpening of the bit, may be accomplished with greater facility 25 than with bits made in accordance with the teaching of the prior art. The entire working face of my bit may be sharpened in one continuous operation, which is impossible with fish-tail bits of the prior art.

30 In the drawing:

Figure 1 shows a perspective view in elevation, of an improved point embodying this invention.

Figure 2 is a front elevation of the lower 35 end of the point shown in Fig. 1.

Figure 3 is a side elevation of the lower end of the point shown in Fig. 1.

This application is a division of my application 219,051 in which I have shown a complete earth boring auger having a point embodying this invention.

The fish-tail point herein disclosed is made of a flat piece of stock 12 which is comparatively thin and has side margins flaring at 45 and 14 to form pointed teeth at the lower

corners. The lower margins of the plane sides of the auger point are oppositely inclined with reference to the central axis of the point and are preferably substantially straight lines, each of which defines the base 50 of one tooth and the cutting edge of the other. The margin 15 forms the base of tooth 13 and the cutting or leading edge of tooth 14, whereas margin 16 comprises the cutting or leading edge of tooth 13 at the 55 base or root of tooth 14. This construction gives the teeth a peculiar rolling bevel and it is found that flaring teeth so bevelled have great adaptability for performing the functions of cutting and breaking shale and the 60 like in addition to the normal function of guiding the auger.

It will be seen that the lower surface of the bit may be described as having been generated by moving a generatrix line in a directrix normal to the front face of the bit and intersecting the axis thereof, and simultaneously swinging the generatrix about the directrix as an axis so that the ends of the generatrix follow two oppositely disposed oblique directrices which constitute lateral edges of the surface; or considered from another point of view, the surface might be described as having been generated by moving a line from left to right of 75 Figure 1 along a central line normal to the narrow surfaces of the piece of stock 12 and simultaneously swinging the generatrix about said normal as an axis and using the edges 15, 16 as secondary directrices for the 80 generatrix to control the extent to which the latter is swung. It will be readily apparent to one skilled in the art that such a surface presents marked advantages from the point of view of sharpening, because the entire 85 working surface of the bit may be sharpened by merely causing a relative movement between the bit and grinding wheel corresponding to the movement of the above described generatrix. Consequently, the entire 90

bit may be sharpened evenly and accurately in a single operation.

In devices of the prior art, it has been necessary to sharpen the two cutting surfaces of a fish-tail bit by two separate and distinct grinding operations. This is disadvantageous not only because the time required is practically twice as much as with the device of the present invention, but also because of the probability that the two surfaces will be ground unevenly. If such uneven grinding occurs, an extremely faulty operation of the bit results. Wobbling and excessive vibration invariably follow an unsymmetrical grinding of a fish-tail bit. Consequently, it is an object of my invention to produce a bit which will always be sharpened with perfect symmetry, thus eliminating the possibility of faulty operation after extensive use.

At its upper end the stock or body member 12 of the point is shouldered at 17 and 18 to provide a tongue-like extension 19 pierced by a hole through which a securing bolt may be extended to anchor the point to the auger.

I claim:

1. A fish-tail auger point comprising a plate having its lower end provided with a rolling bevel varying substantially continuously in angle of inclination from one side of the plate to the other, and having straight line edges extending entirely across said plate the bevel of said lower end being opposite in angle of inclination at opposite side margins of the plate.
2. A fish-tail auger point comprising a relatively thin elongated plate having one of its ends provided with rectilinear edges coextensive with the width of said plate, said end being beveled at opposite angles of inclination at the opposite sides of the plate, the bevel of the end of the plate rolling substantially continuously between the sides of the plate, and the angles of inclination of the oppositely beveled portions at the margins thereof being substantially alike.
3. A fish-tail auger point, comprising a plate having its opposing faces terminating in margins of opposite inclination and teeth formed in the corners of said plate by the inclination of such margins, each margin lying in a straight line defining the leading edge of one tooth and the base of the other.
4. A fish-tail auger point comprising a substantially flat plate flaring at its lower end and provided at such end with a substantially symmetrical rolling bevel surface of substantially equal and opposite inclination at the opposite sides of the plate and varying substantially continuously therebetween, the margins of said surface lying in straight line edges extending substantially across said plate.
5. A fish-tail auger point comprising a substantially flat plate flaring at the sides of its lower end and provided at such end with

oppositely beveled portions terminating in points at the opposite sides of the plate, said oppositely bevelled portions being bounded by substantially straight edges extending entirely across said plate.

6. A fish-tail auger point comprising a flat plate having flaring margins adjacent its lower end, the lower margins of adjacent faces of said plate being oppositely inclined whereby to form teeth at the flaring corners of the plate, each such margin extending in a substantially continuous straight line across said plate and defining the leading edge of one tooth and the root of the other.

7. A fish-tail auger point comprising a flat plate having flaring margins adjacent its lower end, the lower margins of adjacent faces of said plate being oppositely inclined whereby to form teeth at the flaring corners of the plate, each such margin defining the leading edge of one tooth and the root of the other, and each such margin being substantially linear whereby to provide a substantially continuous rolling bevel across the lower end of the plate.

8. A fish-tail bit having two substantially parallel plane faces, each of said faces terminating in a continuous straight line edge extending the full width of said bit, said two edges being oppositely inclined to the axis of said bit, said bit having a bottom surface connecting the said edges and varying in angular relation to said plane surfaces constantly throughout the full width of said bit.

9. A fish-tail bit comprising a substantially flat plate terminating in outwardly flaring points at its lower end, said bit having substantially parallel side faces and a bottom face, said side faces meeting said bottom face in straight line edges extending the full width of said bit from one to the other of said outwardly flared points, said straight line edges being oppositely inclined to the axis of said bit throughout their entire lengths, said bottom face presenting a constantly varying rolling bevelled surface from one of said points to the other.

10. A fish-tail bit comprising a substantially flat plate having substantially parallel side faces and having a bottom surface, said surface being generated by passing a straight line generatrix along and in perpendicular relation to a central directrix normal to said faces and intersecting the axis of said bit, and simultaneously swinging said generatrix about said directrix to cause its ends to follow oppositely disposed oblique directrices, of which latter directrices one is spaced at each side of said first directrix, and defines an edge of said surface.

11. A fish-tail bit comprising a substantially flat plate having substantially parallel side faces and having a bottom surface, said surface being generated by passing a straight line generatrix along and in perpendicular

relation to a central directrix normal to said faces and intersecting the axis of said bit, and simultaneously swinging said generatrix about said directrix to cause its ends to
5 follow oppositely disposed oblique straight line directrices of which latter directrices one is spaced at each side of said first directrix, and defines a straight line edge of said surface.
